Application May 24, 1937, Serial No. 144,340

7 Claims.

(Cl. 1-3)

This invention relates to fastener-applying implements and more particularly to a safety device for such implements which operates to prevent the fasteners from being jammed and deformed or damaged during a refilling or loading operation.

In one known type of fastener-applying implement a refill stick or charge of fasteners is supplied to the magazine at its forward end by sliding them onto a core therein. In this type of implement a pivoted gate is rocked to open the forward end of the magazine and a stick of pre-formed fasteners held together by an adhesive is forced rearwardly into the magazine against the force of a spring-pressed pusher. As the magazine becomes fully loaded the pusher is forced back to the end of the magazine where it engages a suitable abutment or stop. The stick of pre-formed fasteners is then broken close to the forward end of the magazine and the gate closed thereagain. It often happens that several of the fasteners at the forward end of the stick project beyond the end of the core in the magazine so that when the gate is closed the fasteners are jammed between the pusher and gate. Consequently the stick of fasteners is subjected to considerable pressure which may cause it to buckle and the fasteners to ride up one on another, or to be otherwise jammed and deformed so that in subsequent use they are liable to cause clogging in the magazine or the throat through which they are driven.

One of the objects of the present invention is to provide an implement of the type indicated having a magazine with means for preventing jamming or damaging the fasteners by filling the magazine beyond its normal capacity.

Another object of the invention is to provide an implement of the type indicated having a yieldable stop or abutment engaged by the pusher to indicate when the magazine is fully loaded and yielding to accommodate additional fasteners.

Another object of the invention is to provide an implement of the type indicated having a gate or door at the forward end of the magazine to permit fasteners to be supplied thereto and a resiliently pressed stop at the rearward end of the magazine adapted to yield to compensate for the final movement of the gate to closed position.

Still another object of the invention is to provide an implement of the type indicated of simple and compact construction, efficient for performing its intended functions, and adapted for use over long periods of time without repair or replacement of its parts.

Further objects of the improvement are set forth in the following specification which describes a preferred embodiment of the invention, by way of example, as illustrated by the accompanying drawings. In the drawings:

Fig. 1 is a side elevation of a stapling implement incorporating the present invention;

Fig. 2 is a longitudinal sectional view of the implement showing the gate open with a refill stick of fasteners in the magazine and projecting beyond the forward end thereof;

Fig. 3 is a view similar to Fig. 2 showing the gate closed and the yielding abutment or stop moved rearwardly by the pusher to adapt the magazine to accommodate the fasteners which project forwardly beyond its end;

Fig. 4 is a detailed perspective view of the rearward end of the magazine-core showing the abutment or stop yieldingly held in its normal position on the core;

Fig. 5 is a view similar to Fig. 4 showing the abutment engaged by the pusher and moved rearwardly to increase the capacity of the magazine; and

Fig. 6 is a transverse sectional view on line 6-6 of Fig. 1 showing the construction of the magazine-arm.

The yieldable stop or abutment constituting the subject of the present invention is illustrated in the drawings as applied to an implement of the type illustrated and described in the United States Letters Patent No. 2,037,334 to A. H. Maynard, issued April 14, 1936, and employed for applying U-shaped staples to the work. It is to be understood, however, that the invention may be applied to other types of implements or to similar implements for applying other forms of fasteners.

The stapling implement as herein illustrated comprises a base 2 preferably constructed of sheet-metal shaped to form a generally flat rectangular top plate 3 bounded by a depending beveled flange 4. Suitable rubber pads 5 are provided at opposite ends of the base to prevent it from marring the finished surface of a desk top or the like on which it is supported. A clincher-anvil 6 is suitably attached to the flat top-portion 3 of the base 2 at its forward end, while a hinge-block 7 is provided at the rearward end of the base for pivotally mounting the stapling- or magazine-arm 10 thereon. The block 7 is fixedly secured to the base 2 and has a transverse hole for receiving a hinge-pin 11 which extends through aligned apertures in depending flanges 12 on the arm 10 to pivotally mount the latter. The

arm 10 is normally held in raised position as illustrated in Fig. 1 by a leaf-spring 13 fastened at one end to the bottom of the flat portion 3 of the base 2 with its other end engaging a hook-shaped latch 14 depending from the arm and extending through a suitable aperture in the block 7 and top 3 of the base.

The arm 10 comprises a U-shaped channel-member 15, see Fig. 6, constituting a hollow magazine for containing a supply of staples s to be used in the implement with its interior provided with a longitudinally-extending staple support or core 16. The core 16 is of inverted U-shape to adapt it to support staples s straddled across its top and is fixedly secured to the member 15 by welding or other means. Flanges 17 suitably secured to the sides of the channel-member 15, as by welding, overlie the top of the core 16 to form guides for holding the staples in position on the core 16. The forward end of the stapling- or magazine-arm 10 is normally closed by a U-shaped door or gate 20 hingedly mounted thereon. A pin 21 having its ends fixed in the side walls of the gate 20 extends through elongated slots 22 in the sides of the arm 10 to mount the gate thereon and provide for its manual operation to open and close the end of the magazine. Notches 23 are formed in lower edges of the side walls of the gate 20 for co-operation with lugs 24 on the arm 10 to latch the gate in closed position. When the gate 20 is closed its front wall cooperates with the end of the staple-core 16 to form a throat or chute 25 through which the staples are driven. A spring 26 bears at its end against the pin 21 to yieldingly hold the notches 23 in the gate 20 in latched engagement with the lugs 24, see Figs. 2 and 3. The gate 20 is opened by raising it against the action of the spring 26 to release its notches 23 from the lugs 24 and 40 then rocking the gate with the pin 21 acting as a pivot.

A staple-driver 30 positioned in the throat 25 is adapted to be reciprocated to drive staples advanced along the core 16 into position beneath the driver. The driver 30 is detachably connected to a lever 31 which overlies the arm 10. As herein illustrated, the lever 31 is of a hollow construction with its sides overlapping and enclosing the sides of the arm 10. The rearward end of the lever 31 is pivoted on a pin 32 passing through the sides of the arm 10. A pad or finger-piece 33 is provided at the forward end of the lever 31 for pressing the arm 10 toward the base 2 and thereafter rocking the lever about its pivot-pin 32 to reciprocate the driver 30 and drive the staples s through the throat 25.

The staples s are advanced along the core 16 and into the throat 25 by a slidable staple-pusher 35. The pusher 35 is of inverted U-shape construction to adapt it to fit closely about the core 16 at the rear of the staples s. A spring 36 has one end connected to an upstanding lug 37 on the pusher 35 and extends forwardly around a suitable cross-strut 38 and then rearwardly 65 with its opposite end connected to a yoke 39 which embraces the pin 32. The spring 36 thus acts to yieldingly urge the pusher 35 forwardly to successively advance the staples s into the throat 25.

70 A staple-retainer 40 is provided on the arm 10 for engaging the staples s to prevent them from being ejected from the magazine by the pusher 35 when the gate 20 is opened; while also being adapted to yield to permit a stick of the staples 75 to slide thereunder when the magazine is being

refilled. The retainer 40 is pivotally mounted on a cross-pin 41 extending between the side walls of the channel-member 15 and has a pointed beak 42 which is adapted to engage the staples in the magazine through an opening 43 between the flanges 17, see Fig. 2. The retainer 40 is held in either one or the other of two positions by a hairpin spring 44 connected to the arm 10 at one end and having its opposite end pivotally connected to the retainer.

In accordance with the present invention the rearward movement of the staple-pusher 35 is limited by its engagement with a yielding stop or abutment 50. In the present embodiment of the invention, as shown most clearly in Figs. 4 and 5, 15 the abutment or stop-member 50 comprises a sheet-metal plate bent to channel-form to provide depending flanges 51 and 52 and a laterally-extending wing 53. The side flange 51 engages one side of the core 16 while the opposite flange 52 is positioned in a longitudinal slot 54 extending forwardly from the rearward end of the core. The flanges 51 and 52 thus provide guides for preventing the abutment 50 from twisting on the core 16 and the abutment is held from rising on the core by the flanges 17 which overlie its top and the lateral wing 53. The forward end of the flange 52 is yieldingly held in engagement with the forward end of the slot 54 by means of a spring 55 within the core 16. The spring 55 30 has a hook 56 at one end which engages a suitable recess 57 in the wing 53 and the opposite end of the spring is connected to a depending lug 58 cut away from the top of the core 16 and bent downwardly therefrom. The spring 55, being 35 thus positioned beneath the top of the hollow core 16, cannot interfere with the normal operation of the pusher 35. With the form of abutment 50 as herein illustrated the forward edge of its channeled portion and the laterally-extending wing 53 provide offset shoulders 60 and 61 which are engaged by correspondingly-shaped offset shoulders 62 and 63 on the pusher 35. The method of operation of the complete device is as next explained.

To load the magazine in the arm 10 with a refill of staples s the gate 20 is first lifted and then rocked on its pivot 21 to open position as illustrated in Fig. 2. The refill stick of staples s may then be inserted in the magazine at its forward end and slid rearwardly on the core 16 beneath the guide-flanges 17. The rearward movement of the staple-stick causes the pusher 35 to be slid rearwardly on the core 16 until its shoulders 62 and 63 engage the shoulders 60 and 61 of the abutment or stop-member 50 which indicates that the magazine is fully loaded. During the charging of the magazine the staple-retainer 40 yields to permit the staple-stick to slide thereunder but dogs on the staples s to prevent their movement outwardly from the magazine under the action of the spring 36 and staple-pusher 35. The refill stick of staples is broken adjacent the forward end of the magazine-arm and the gate 20 is then rocked about its pivot 21 to its closed position shown in Fig. 1.

Should the end of the refill stick project beyond the end of the core as indicated in Fig. 2, the foremost staple is engaged by the front wall of the gate 20 as the latter is rocked to its closed position which thereby forces the staple-stick rearwardly in the magazine. This motion is transmitted to the staple-pusher 35 and due to the engagement of its shoulders 62 and 63 with the shoulders 60 and 61 on the abutment 50 the 75

latter is caused to be moved rearwardly to a limited extent to increase the capacity of the magazine whereof to accommodate the few additional staples. The spring 55 yields to permit this limited rearward movement of the abutment 50 so that the combined action of the springs 55 and 36 thereafter urges the pusher 35 forwardly. Due to the yielding action of the spring 55 the staple-stick is prevented from being buckled and the staples from being deformed or otherwise damaged so that subsequent clogging in the throat 25 is obviated.

The closing of the gate 20 rocks the retainer 40 to release its beak 42 from engagement with the staples *s* so that the pusher 35 may then advance the staples forwardly in the magazine-arm 10. The foremost staple is thus positioned in the throat 25 beneath the driver 30 and when the lever 31 is depressed relatively of the arm 10 the driver shears the staple from the stick and drives it downwardly through the throat. The lever 31 is then returned to the position shown in Fig. 1 by a suitable spring, not herein shown, to raise the driver 30 above the staple-core 16. The staple-pushers 35 then acts under the tension of the spring 36 to advance the staples forwardly in the magazine-arm 10 to position another staple beneath the driver to be driven in the manner as first explained. During the advance of each successive staple into driving position the abutment 50 is moved forwardly by the spring 55 until eventually the forward end of the depending flange 52 engages the forward end of the slot 54 in the core 16. The abutment 50 is then prevented from further forward movement and the staples *s* are advanced successively by the pusher 35 until the supply is exhausted. A new stick of staples may then be supplied to the magazine-arm 10 in the manner as above explained, the engagement of the pusher 35 with the abutment 50 indicating when the magazine is fully loaded and the abutment yielding to accommodate a few additional staples on the stick which may project forwardly beyond the end of the core 16.

It will be observed that the yielding abutment in the magazine acts to enlarge its capacity to prevent jamming or deformation of staples during a refilling or loading operation. It will further be observed that the yielding abutment is of simple and compact structure, adapting it for economical manufacture and convenient assembly with the other parts of the implement without material alteration in the form thereof.

While the improved device is herein described and illustrated as embodied in a preferred form of construction, it is to be understood that various modifications may be made in the structure and arrangement of its parts without departing from the spirit or scope of the invention. Therefore, without limiting myself in this respect, I claim:

1. In a fastener-applying implement, a magazine for holding a supply of fasteners, a pusher for feeding the fasteners from the magazine, means for actuating the pusher to advance the fasteners in the magazine, a stop adapted to be engaged by the pusher when a predetermined number of fasteners are placed in the magazine, and resilient means acting on said stop to adapt it to yield to increase the normal capacity of the magazine.

2. In a fastener-applying implement, a magazine having a core for supporting a series of fasteners applied to the core at its forward end, a pusher slidable on the core, means for actuating

the pusher to advance the fasteners along the core, an abutment adapted to be engaged by the pusher during its rearward movement when a predetermined number of fasteners are placed in the magazine, and resilient means acting on the abutment to adapt it to yield when the number of fasteners supplied exceeds the normal capacity of the magazine.

3. In a fastener-applying implement, a magazine for holding a supply of fasteners, a pusher slidable in the magazine for advancing the fasteners to feed them therefrom, a spring for actuating the pusher to advance the fasteners in the magazine, an abutment in the magazine adapted to be engaged by the pusher when the fasteners are placed in the magazine, means to permit loading of the magazine, and a spring cooperating with the abutment to adapt the latter to yield when the supply of fasteners is greater than that normally allowed between the abutment and the end of the magazine.

4. In a fastener-applying implement, a magazine for holding a supply of fasteners, a pusher slidable in the magazine, means for actuating the pusher to advance the fasteners in the magazine, means for opening one end of the magazine to insert the fasteners thereinto, and yieldable means engaged by the pusher when a predetermined number of the fasteners are placed in the magazine, said last-named means yielding to increase the capacity of the magazine to accommodate additional fasteners.

5. In a fastener-applying implement, a magazine for holding a supply of fasteners, a core in the magazine for supporting the fasteners, a gate at the forward end of the magazine cooperating with the core to form a throat through which the fasteners are driven, said magazine being loaded with a supply of fasteners when the gate is open by sliding them rearwardly onto the core, a pusher for advancing the fasteners along the core and into the throat, an abutment at the end of the core adapted to be engaged by the pusher during its rearward movement thereon, and a spring acting on the abutment and yieldable to prevent jamming or deformation of the fasteners when the gate is moved to closed position and the number of fasteners inserted exceeds the normal capacity of the magazine.

6. In a stapling or wire-stitching machine, a magazine for holding a supply of preformed staples, a pusher slidable in the magazine to advance the staples therein, a hinged gate at the end of the magazine operable to permit staples to be supplied thereto, and yieldable means for engaging the pusher when a predetermined number of staples are placed in the magazine to limit its movement while preventing the staples from being jammed or deformed by the closing of the gate when the supply of staples is greater than the normal supply and extends slightly beyond the magazine at the gate end.

7. In a fastener-applying implement, a magazine for holding a supply of fasteners inserted at its forward end, means for advancing the fasteners in the magazine to feed them therefrom, and yieldable means in the magazine independent of the feeding means and engageable by the latter during its rearward movement when fasteners are placed in the magazine, said last-named means yielding to prevent buckling or deformation of the fasteners when the number of fasteners supplied exceeds the normal capacity of the magazine.
